DE NEMOURS & COMPANY, OF WILMINGTON, DELAWARE

FEEDING APPARATUS FOR THE DELIVERY OF RECEPTACLES TO FILLING APPARATUS
OR THE LIKE

Application filed July 30, 1928, Serial No. 296,206, and in Great Britain August 12, 1927.

This invention refers to feeding apparatus for the delivery of tubular cylindrical receptacles, hereinafter referred to as tubular receptacles, to filling devices or the like, hereinafter referred to generally as fillers, with which the tubular receptacles are required to be assembled by application endwise, a receptacle upon a filler, a group of fillers being provided, the fillers of a group being parallel to one another and spaced apart, the intervening spaces generally being equal. In the claims such apparatus will be referred to as apparatus of the type defined for the delivery of tubular receptacles to filling devices.

Apparatus according to this invention is particularly suitable for dealing with tubular receptacles of a pliable nature which offer little resistance to deformation, composed say of paper or the like, for example, such as may be used as described in the specification of United States Patent No. 1,697,831, dated 1st January, 1929.

According to this invention provision is made for maintaining tubular receptacles stacked, lying horizontally, one higher than another, and for moving alternate receptacles endwise from a stack for delivery onto fillers. Thus, the first (say the lowest receptacle) of the stack, the third, the fifth, and so on. Normally, and in the initial process of delivery, the second, the fourth, and so on, intervening receptacles, act temporarily as spacing members, and after removal of the first, third and so on, the stack is restored by other receptacles moving down. Thus, the receptacles of a stack are arranged in single file. Further, provision may be made for relieving the lower receptacles in a stack from part of the weight of those above. Further, the invention relates to means for pushing the receptacles from a stack, to means for guiding a receptacle as it passes out of a stack onto a filler, and for affording external support to a receptacle in the process of its being assembled with a filler.

By way of example according to this invention a hopper is provided having a passage (or passages) of a width corresponding approximately with the outside diameter of

a receptacle. This passage extends downwardly, is open at its upper end and is closed at its lower end, so that tubular receptacles may be introduced at the upper end and be stacked in the passage, lying horizontally, one against another, one, the first, resting against the closed lower end of the passage, the second receptacle against the first, and so on. The passage might extend vertically downwards, but generally for receptacles of an easily deformable nature the passage is not vertical or a part of it is not vertical, for example, it is inclined. In a vertical passage the first receptacle would be subjected to the weight of those stacked above it, whereas in an inclined passage the weight to which the lower receptacles would be subjected is reduced.

The front and the back of a hopper of this kind have apertures located co-axially with the positions which alternate receptacles in the lower part of the stack occupy in the passage from which delivery is to be made, and in making provision for pushing a tubular receptacle endwise from a stack onto a tubular filler, the filler is situated co-axially with an aperture at the front of the hopper and extends horizontally being in alignment or approximately so with the receptacle in the stack. Thus, a first filler is situated endwise opposite a first receptacle, and, if there is more than one filler, a second filler opposite the third receptacle, and, if there are more than two fillers, a third filler opposite the fifth receptacle, and so on. Thus, in the case of two or more fillers, receptacles in a stack act as distancing members for receptacles which are to be pushed out endwise.

In construction, series of passages may be provided. For example, the passages may extend downwardly to positions which at their lower ends are in vertical or approximately vertical alignment, and two complementary series of passages may be provided extending from positions at the upper end on opposite sides of a vertical central line.

For pushing the receptacles endwise from a hopper, plungers are provided one for each receptacle to be fed forward. Thus, for a series of passages a group of plungers are

provided. With tubular receptacles closed at one end, the back end, the plungers are formed to act against the back ends.

With apparatus according to this invention provision may be made for guiding a receptacle as it is pushed from its passage and for affording it support.

To ensure that the receptacles stack properly, one resting on the one below, they may be subjected to vibration, say, when the plungers are withdrawn. For example, one or both sides of a passage, say the upper parts, the vertical parts only of a passage, may be reciprocated while the plungers are withdrawn. Further, the hopper may comprise a feed portion and a bulk supply container, with provision for intermittently supplementing the supply, say, by valve control, from the bulk supply container to the feed portion.

An example of apparatus according to this invention will now be described with reference to the accompanying drawings, in which:—

25 Figure 1 is a sectional front elevation, and Figure 2 is a plan of the apparatus.

Figures 3, 4, 5 and 6 are diagrams, longitudinal sectional side elevations, illustrating the process of operation.

30 Figure 7 is a side elevation showing a detail of mechanism.

The drawings show:—Tubular receptacles A. Hopper B. Passages C in hopper B. Plungers D. Guide E. Fillers F. Each 35 passage C is open at its upper end, is closed at its lower, its upper part is vertical and its lower part inclined. Two series of passages are shown arranged substantially symmetrically on opposite sides of a vertical central 40 line. In each series the closed lower ends of the passages are in alignment vertically. Walls 3 of the upper parts of the passages are movable vertically and are connected by a frame 4 with the piston of a cylinder 5 by 45 which they are reciprocated.

In Figure 1 tubular receptacles A are shown stacked in the passages C. For each passage in the back of the hopper B, see Figures 3-6 apertures 6 are formed and in the 50 front apertures 7, these apertures are situated co-axially with the positions which alternate tubular receptacles 2 occupy in the passages. The plungers D and fillers F are co-axial with the apertures 6, 7 and tubular receptacles 2.

55 The plungers D, see Figure 2, are carried upon a crosshead 8 which is connected by a rod with the piston of a cylinder 9, by which they are moved endwise. The guide E, see Figures 2 and 3-6, situated at the front 60 of the hopper is formed with tapered apertures 10 which are co-axial with the apertures 6, 7, and is movable endwise away from and towards the front of the hopper. For this purpose as indicated at 65 Figure 7, trip devices are provided, one at

each side, each consisting of a link G which by slot and pin 13 is connected with crosshead 8, pin 13 being on 8, and link G, by latch and pin 14 engages with guide E, pin 14 being on guide E, and for the link G a step 15 is provided.

Figures 3, 4, 5, and 6 illustrate positions and process of operation. Thus, Figure 3 shows part of a passage C, a tubular receptacle 2, which is closed at its back end 2¹, and one other receptacle A in the passage above 2, and with the plunger D and guide E in what may be termed their first positions. Figure 4 shows a second position, resulting from movement endwise of plunger D, while guide E stands close to the front of hopper B and is stationary, receptacle 2 having been moved so that its front has passed through aperture 7 and been moved to the delivery end of aperture 10, in this movement, see Figure 7, pin 13 will have travelled from left to right in its slot in link G. Figure 5 shows a third position, resulting from movement endwise together, forwardly of plunger D, receptacle 2, and guide E, which brings the front end of receptacle 2 to the outer end of filler F to which it is to be applied, in this movement link G moves with pin 13 and near the end of this movement link G by riding up step 15 is disengaged from pin 14, whereby guide E is left to stand stationary. Figure 6 shows the delivery of the receptacle 2 onto filler F, completed, in the process of which guide E, remains stationary while plunger D acts temporarily for the support of receptacle A. Afterwards the plunger D is withdrawn from the passage, and as soon as withdrawn the walls 3 are reciprocated, cylinder 5 being brought into action, and the conditions indicated at Figure 3 are again established.

In Figure 1 there is shown a bulk supply container H provided with a shutter base 16. A container of this kind may be kept ready charged so that when the supply has been worked down to the top of hopper B, working may be continued while the empty container H is removed and another charged container H is placed in position, its shutter 16 is then withdrawn and the supply to hopper B renewed.

I claim:—

1. Apparatus of the type defined for the delivery of tubular receptacles to filling devices, comprising a hopper having passages for maintaining tubular receptacles, stacked, lying horizontally, one higher than another, and means for moving alternate receptacles endwise from the stack for delivery onto fillers.

2. Apparatus of the type defined for the delivery of tubular receptacles to filling devices, comprising a hopper having passages for maintaining tubular receptacles, stacked,

lying horizontally, one higher than another, the passages being formed so that lower receptacles in a stack are relieved from part of the weight of those above, and means for moving alternate receptacles endwise from the stack for delivery onto fillers.

3. Apparatus of the type defined for the delivery of tubular receptacles to filling devices, comprising a hopper having passages for maintaining tubular receptacles, stacked, lying horizontally, one higher than another, the lower part of each passage being inclined, and means for moving alternate receptacles endwise from the stack for delivery onto fillers.

4. Apparatus of the type defined for the delivery of tubular receptacles to filling devices, comprising a hopper having passages for maintaining tubular receptacles, stacked, lying horizontally, one higher than another, the upper part of each passage being vertical, the lower part of each passage being inclined, and means for moving alternate receptacles endwise from the stack for delivery onto fillers.

5. Apparatus of the type defined for the delivery of tubular receptacles to filling devices, comprising a hopper having passages for maintaining tubular receptacles, stacked, lying horizontally, one higher than another, means for subjecting receptacles in the passages to agitation, and means for moving alternate receptacles endwise from the stack for delivery onto fillers.

6. Apparatus of the type defined for the delivery of tubular receptacles to filling devices, comprising a hopper having passages for maintaining tubular receptacles, stacked, lying horizontally, one higher than another, a wall of each passage being movable, reciprocated, and means for moving alternate receptacles endwise from the stack for delivery onto fillers.

7. Apparatus of the type defined for the delivery of tubular receptacles to filling devices, comprising a hopper having passages for maintaining tubular receptacles, stacked, lying horizontally, one higher than another, the hopper having a feed portion, a bulk supply container for the feed portion of the hopper, and means for moving alternate receptacles endwise from the stack for delivery onto fillers.

8. Apparatus of the type defined for the delivery of tubular receptacles to filling devices, comprising a hopper having passages for maintaining tubular receptacles, stacked, lying horizontally, one higher than another, means for moving alternate receptacles endwise from the stack for delivery onto fillers, and means for guiding and affording support to each receptacle as it is moved endwise from its stack.

9. Apparatus of the type defined for the delivery of tubular receptacles to filling de-

vices, comprising a hopper having passages for maintaining tubular receptacles, stacked, lying horizontally, one higher than another, means for moving alternate receptacles endwise from the stack for delivery onto fillers, a guide presenting for each receptacle in delivery a bore tapered at its entry end and at its discharge end of substantially the same diameter as the outside of a receptacle, for the purposes set forth.

10. Apparatus of the type defined for the delivery of tubular receptacles to filling devices, comprising a hopper having passages for maintaining tubular receptacles, stacked, lying horizontally, one higher than another, means for moving alternate receptacles endwise from the stack for delivery onto fillers, guide means for guiding and affording support to each receptacle as it is moved endwise from its stack, and means for operating said guide means whereby in the process of the delivery of a receptacle said guide means are held stationary to receive the front end of the receptacle, then are moved forwardly with the receptacle to bring the front end of the receptacle over the end of its filler and then are held stationary during the completion of delivery onto the filler.

11. Apparatus of the type defined for the delivery of tubular receptacles to filling devices, comprising a hopper having passages, each passage extending downwardly and of a width corresponding approximately with the diameter of a receptacle, the passages being open at their upper ends and closed at their lower ends, apertures in the front and in the back of the hopper in the region of the lower part of each passage from which delivery is to be made, said apertures being co-axial with the positions which alternate tubular receptacles stacked, lying horizontally, one against another, occupy in a passage, a group of plungers at the back of the hopper and a group of fillers at the front of the hopper, the plungers and fillers being co-axial with the apertures, the plungers being movable endwise forwardly for pushing alternate receptacles endwise from the passages, the fillers being located with their ends at the front of the hopper for the receptacles to pass onto, and the plungers being movable endwise backwardly for withdrawal from the passages.

12. Apparatus of the type defined for the delivery of tubular receptacles to filling devices, comprising a hopper having passages, each passage extending downwardly and of a width corresponding approximately with the diameter of a receptacle, the passages being open at their upper ends and closed at their lower ends and the lower part of each passage being inclined, apertures in the front and in the back of the hopper in the region of the lower part of each passage from which delivery is to be made, said passages being

- co-axial with the positions which alternate tubular receptacles stacked, lying horizontally, one against another, occupy in a passage, a group of plungers at the back of the hopper and a group of fillers at the front of the hopper, the plungers and fillers being co-axial with the apertures, the plungers being movable endwise forwardly for pushing alternate receptacles endwise from the passages, 50 the fillers being located with their ends at the front of the hopper for the receptacles to pass onto, the plungers being movable endwise backwardly for withdrawal from the passages, means for subjecting receptacles in the passages to agitation preparatory to delivery, and means for guiding and affording support to each receptacle as it is moved endwise in delivery from its stack. 70
- JAMES GEORGE JACKSON. 75
13. Apparatus of the type defined for the delivery of tubular receptacles to filling devices, comprising a hopper having passages, each passage extending downwardly and of a width corresponding approximately with the diameter of a receptacle, the passages being open at their upper ends and closed at their lower ends, the upper part of each passage being vertical, the lower part of each passage being inclined, the upper parts of the 80 passages being substantially symmetrical on opposite sides of a vertical central line and their closed lower ends extending to or near the vertical central line, apertures in the front and in the back of the hopper, in the region of the lower part of each passage from which delivery is to be made, said passages being co-axial with the positions which alternate tubular receptacles stacked, lying horizontally, 85 one against another, occupy in a passage, a group of plungers at the back of the hopper and a group of fillers at the front of the hopper, the plungers and fillers being co-axial with the apertures, the plungers being movable endwise forwardly for pushing alternate receptacles endwise from the passages, the fillers being located with their ends at the front of the hopper for the receptacles to pass onto, and the plungers being 90 movable endwise backwardly for withdrawal from the passages. 95
14. Apparatus of the type defined for the delivery of tubular receptacles to filling devices, comprising a hopper, having passages, each passage extending downwardly and of a width corresponding approximately with the diameter of a receptacle, the passages being open at their upper ends and closed at their lower ends, apertures in the front and in the back of the hopper, in the region of the lower part of each passage from which delivery is to be made, said passages being co-axial with the positions which alternate tubular receptacles stacked, lying horizontally, one against another, occupy in a passage, a group of plungers at the back of the hopper and a group of fillers at the front of the hopper, the plungers and fillers being co-axial with the apertures, the plungers being 100 movable endwise forwardly for pushing alternate receptacles endwise from the passages, the fillers being located with their ends at the front of the hopper for the receptacles to pass onto, and the plungers being 105 movable endwise backwardly for withdrawal from the passages. 110
15. Apparatus of the type defined for the delivery of tubular receptacles to filling devices, comprising a hopper, having passages, each passage extending downwardly and of a width corresponding approximately with the diameter of a receptacle, the passages being open at their upper ends and closed at their lower ends, apertures in the front and in the back of the hopper, in the region of the lower part of each passage from which delivery is to be made, said passages being co-axial with the positions which alternate tubular receptacles stacked, lying horizontally, one against another, occupy in a passage, a group of plungers at the back of the hopper and a group of fillers at the front of the hopper, the plungers and fillers being co-axial with the apertures, the plungers being 115 movable endwise forwardly for pushing alternate receptacles endwise from the passages, the fillers being located with their ends at the front of the hopper for the receptacles to pass onto, and the plungers being 120 movable endwise backwardly for withdrawal from the passages. 125
16. Apparatus of the type defined for the delivery of tubular receptacles to filling devices, comprising a hopper, having passages, each passage extending downwardly and of a width corresponding approximately with the diameter of a receptacle, the passages being open at their upper ends and closed at their lower ends, apertures in the front and in the back of the hopper, in the region of the lower part of each passage from which delivery is to be made, said passages being co-axial with the positions which alternate tubular receptacles stacked, lying horizontally, one against another, occupy in a passage, a group of plungers at the back of the hopper and a group of fillers at the front of the hopper, the plungers and fillers being co-axial with the apertures, the plungers being 130 movable endwise forwardly for pushing alternate receptacles endwise from the passages, the fillers being located with their ends at the front of the hopper for the receptacles to pass onto, and the plungers being movable endwise backwardly for withdrawal from the passages. 135
